[57] CLAIM

The ornamental design for a digital clock, substantially as shown and described.

DESCRIPTION

FIG. 1 is a front elevational view of a digital clock showing my new design;

FIG. 2 is a top plan view thereof;

FIG. 3 is a right side elevational view thereof;

FIG. 4 is a rear elevational view thereof;

FIG. 5 is a front elevational view of a second embodiment of my new design of FIGS. 1-4;

FIG. 6 is a front elevational view of a third embodiment of my new design of FIGS. 1-4;

FIG. 7 is a front elevational view of a fourth embodiment of my new design of FIGS. 1-4;

FIG. 8 is a front elevational view of a fifth embodiment of my new design of FIGS. 1-4;

FIG. 9 is a front elevational view of a sixth embodiment of my new design of FIGS. 1-4;

FIG. 10 is a front elevational view of a seventh embodiment of my new design of FIGS. 1-4;

FIG. 11 is a front elevational view of an eighth embodiment of my new design of FIGS. 1-4;

FIG. 12 is a front elevational view of a ninth embodiment of my new design of FIGS. 1-4.

The rear, top and side views of the second through ninth embodiments are identical in shape to those of FIGS. 2-4, differing only in the surface decoration appropriate to each design embodiment.
